(76) Inventor: **Rowland Cromelon**

Rowland Commlin, of New York
Letters Patent

The Schedule referred to in these Letters Patent, and making part of the same, containing a description in the words of the said Rowland Commlin, himself, of his Improvement in the mode of manufacturing Mattresses, sofa, and other articles.

To all whom it may concern,

Doth Almon that I, Rowland Commlin, of the City of New York, have invented an Improvement in the mode of Manufacturing Mattresses, sofa, and other articles requiring an elastic stuffing, and that the following is a full and exact description of my said invention.

Although the plan of making Mattresses adopted by me is applicable to a variety of other articles, these various applications will be readily understood by every workman, from a single example, I shall therefore confine my description to the mode of procedure in manufacturing the one first named.

The foundation of my Mattress is a framework of wood and usually

of white pine which is preferred on account of its lightness.

When the mattress is not intended to fold up, I first take two lattice work frame, which may be made of stuff cut into strips about three inches wide, and from three fourths of an inch to one inch in thickness.

Four of these strips form the outside of each frame, which is to be of the size of the mattress to be made. Other strips are framed across either to form oblong squares, like the rails of a window sash, or any other shape which may be preferred. These strips are halved together where they cross each other, and are securely fastened, so as to render the frame sufficiently strong, without being heavy.

Between the two frames thus prepared, I insert springs made of iron or steel wire. These springs are made in a spiral form, and they are generally wound so that their out line is that of two cones jointed together at their apices, they however may be wound in other forms, and still produce the same effect. The springs are firmly fixed at each end to the frames before mentioned, thus uniting them by a medium possessing great elasticity. The number of these springs will depend upon the size of the mattress, and that of the wire used, in mattresses of the larger size, from thirty to forty will be found sufficient. The wire which I generally use is from number eight to number ten; and the length of the spring when wound may vary from eight inches to ten, I usually fasten them to the frames by means of wire staples.

In many instances great advantage has been derived by invalids from sleeping upon an inclined plane, instead of the usual horizontal position, and attempts have been made, but not successfully to give a regular inclination from the head to the foot to mattresses made in the common way; but upon my principle this is readily and perfectly effected, all that is necessary being to vary the height of the springs regularly, in proceeding from the head to the foot.

After the springs have been fixed in their places, that frame which is intended to form the upper side of the mattress is to have strong canvas, or other cloth, stretched over it and secured by nailing at the edges of the frame. This cloth is also to be carried down and tacked to the bottom frame so as to form the sides and ends of the mattress, and to bring the two frames to a proper distance from each other. Upon the top of this canvas, curled hair is to be spread evenly, from ten to fifteen pounds being sufficient for a large mattress. The ticking, properly prepared, is then laid over the

hair, is tacked at the edges of each frame and bound in the usual manner. It is then quilted down to the upper side. To prevent any improper longitudinal or lateral motion of the frames, I employ small iron, or other wire to brace them. The pieces of wire so used are cut to a convenient length, say two or three feet, one end of each is fastened to the upper, and one to the lower frame, passing diagonally, and in crossed directions from eight to a dozen being used.

When the mattress is to be doubled up, so as to be portable, each of the frames, before described, may be divided into two parts; and the upper frame hinged together, with two, three, or more hinges, according to its size; it may be then doubled over, so as to bring the two ends of the mattress, nearly into contact. If the under frame latches or bolts properly constructed, are to be affixed, for securing the divided frames together, when in use.

I do not claim the application of springs, such as I have described, so as to produce elasticity, in the mattresses, sofas, and other articles, these having been before exemplified; but I claim as my invention, the attaching them to frames of wood, for the purposes, and in the manner, hereinbefore set forth. I also claim the use of the diagonal braces, whether made of wire or other material.

Witnesses.
